(57) **CLAIM**

The ornamental design for a lamp shade assembly, as shown and described.

DESCRIPTION

The file of this patent contains at least one drawing/photograph executed in color. Copies of this patent with color drawing(s)/photograph(s) will be provided by the Office upon request and payment of the necessary fee.

1. Lamp shade assembly

1.1 : Perspective

1.2 : Front

1.3 : Back

1.4 : Left

1.5 : Right

1.6 : Top

1.7 : Bottom

1.8. Reference

The portions colored yellow shown in Figures 1.1-1.7 form no part of the claimed design. Figure 1.8 is a reference view showing the claimed design in condition of use and forms no part of the claimed design.
